UNITED STATES PATENT OFFICE.

CHARLES A. BARTLIFF, OF ST. LOUIS, MISSOURI.

DESIGN FOR A PUMP-CURB.

SPECIFICATION forming part of Design No. 28,190, dated January 18, 1898.

Application filed December 20, 1897. Serial No. 662,759. Term of patent 14 years.

To all whom it may concern:

Be it known that I, CHARLES A. BARTLIFF, a subject of the Queen of Great Britain, residing at the city of St. Louis, State of Missouri, have invented a certain new and original Design for a Pump-Curb, of which the following is a full, clear, and exact description, reference being had to the accompanying drawings, forming part of this specification, in which—

10 Figure 1 is a side elevational view of a pump-curb ornamented according to my new design, and Fig. 2 is a top plan view of the same.

This invention relates to a new and original design for pump-curbs; and it consists, generally stated, in the shape and ornamentation of the same, as will hereinafter be described and afterward pointed out in the claim.

15 The general features of my new and original design in pump-curbs consists in the shape of the body portion and the shape and ornamentation of the top.

20 In the drawings, the body portion consists of two side walls A, which are formed with a centrally curved or bulged portion, as shown

in dotted lines in Fig. 2, said side walls gently tapering off toward the end walls B, to which they are connected with rounded corners.

C indicates the top, around whose lower edge is arranged a beading c. The side and end walls of this top C conform substantially to the top and end walls of the body of the curb.

The top plate D extends slightly beyond the side and end walls of the cover C, forming a flange d. This top plate D is formed with a crown terminating at each end in reverse curves, making substantially a compound curve.

Having thus described my new design, what I claim is—

The design for a pump-curb, substantially as herein shown and described.

In testimony whereof I hereunto affix my signature, in the presence of two witnesses, this 13th day of December, 1897.

CHARLES A. BARTLIFF.

Witnesses:

F. R. CORNWALL,
HUGH K. WAGNER.
